United States Patent Office

Des. 206,992
Patented Feb. 21, 1967

206,992

HAIR PROTECTOR

Herman Skier, 16 E. 42nd St., Brooklyn, N.Y. 11203

Filed May 4, 1966, Ser. No. 2,163

Term of patent 14 years

(Cl. D2—253)

FIG. 1

FIG. 2

FIG. 3

FIG. 4

FIG. 1 is a front perspective view of a hair protector embodying my new design, the broken line showing of the wearer is for purposes of illustration only;

FIG. 2 is a top plan view thereof;

FIG. 3 is a rear elevational view; and

FIG. 4 is a side elevational view.

I claim:

The ornamental design for a hair protector, substantially as shown and described.
